Patented Dec. 27, 1910.

UNITED STATES PATENT OFFICE.

ELIJAH D. McDONALD, OF LOS ANGELES, CALIFORNIA.

REINFORCED-CONCRETE PILE.

979,529.

Specification of Letters Patent. Patented Dec. 27, 1910.

Application filed January 13, 1910. Serial No. 537,923.

To all whom it may concern:

Be it known that I, ELIJAH D. McDONALD, a citizen of the United States, residing in Los Angeles, county of Los Angeles, and 5 State of California, have invented a new and useful Reinforced-Concrete Pile, of which the following is a specification.

This invention relates to reinforced concrete piles and the main object of the invention is to so construct the pile that it may be driven into place by jetting, and to provide improved means for enabling the process of jetting to be performed much quicker and easier than by constructions 15 heretofore employed; it being possible, with my construction, to sink a pile by jetting through not only sand, but a bed harder than sand, such as clay or hard-pan.

A further object of the invention is to 20 provide a pile of this character which may be sunk in the bed of the ocean and a sufficient number located side by side and close together to form a continuous wall.

A further object of the invention is to so 25 construct the pile that when built in the wall, all of the piles forming the wall are interlocked with each other against lateral displacement; a further object being to key the several piles together so that they are 30 also locked against displacement in a direction longitudinally of the line of the wall.

Other objects and advantages will be brought out in the following description.

The accompanying drawings illustrate 35 the invention and referring thereto, Figure 1 is a horizontal section through the pile, showing a portion of an adjacent pile in plan, to illustrate the interlocking of the piles; Fig. 2, is a vertical longitudinal section 40 through a pile on line x^2-x^2 , Fig. 1; Fig. 3, is a vertical longitudinal section through a cylindrical form of pile; Fig. 4, is a horizontal section on line x^4-x^4 , Fig. 3. Fig. 5 is a perspective view of the form 45 of pile shown in Figs. 1 and 2; Fig. 6, is a plan view showing the manner of constructing the wall of the piles.

In the form shown in Figs. 1, 2, 5 and 6, each pile comprises a concrete monolith 1 50 substantially rectangular in cross-section but formed with vertically projecting flanges 2 arranged at diagonally opposite corners, the width of each projecting flange 2 being one-half the width of the pile, so that the piles 55 may be joined together with the flanges 2 overlapping and interlocking, as shown in

Figs. 1 and 6, and producing flush inner and outer surfaces of the wall. Each flange 2 is formed with a longitudinal groove 3 which registers with the groove 3 on the flange of 60 the adjoining block, thus forming a circular hole into which concrete is poured to form a key 4 which serves to lock the piles together against displacement in a line longitudinal of the wall. The overlapping flanges 2 prevent the lateral displacement of the piles. 65

Each pile is formed with horizontal footings 5 at the bottom which serve as supports for the pile. Around the footings 5 is a downwardly directed flange 6 secured to the 70 footings by spikes 7 or in any other convenient manner. The flange 6 forms a space 8 at the bottom of the pile, the purpose of which will be described.

Extending longitudinally of the pile are 75 numerous metallic reinforcements which may be of any preferred construction, such for example as the twisted wire rods 9. These rods project above each pile, as shown in Fig. 5, for a slight distance to form an 80 anchorage for a superposed pile. Numerous cross rods 10 extend parallel with the outer and inner faces of the pile and rods 10' extend laterally and preferably at an angle, as shown in Fig. 1, in order that they may be 85 more perfectly distributed in the monolith. The vertical rods 9 are also arranged in rows, as shown in Fig. 1, which rows are inclined and substantially parallel with the cross rods 10' to secure even distribution of 90 reinforcement throughout the monolith.

Extending through the footings 5 are inlet pipes 11 and outlet pipes 12, the respective pipes 11 and 12 communicating with the recess 8 within the flange 6, and preferably being staggered as shown. The purpose of these pipes is to enable water or water with an abrasive, to be introduced into the space 8 and directed against the sand or other earth stratum at the bottom of the pile to 100 loosen and break up the same and for the removal of it from the space 8. The water under pressure is introduced through the pipes 11 and is directed with force against the sand or other material at the bottom of 105 the pile and loosens and removes the same from the area within the flange, while suction is maintained through the pipes 12, so that as fast as the material which has been loosened by the jetting action of the water 110 entering from the pipes 11, accumulates in the space 8 within the flange 6, it is re-

moved immediately by the suction in pipes 12. As the material at the bottom of the pile is thus continually removed, the pile sinks. The provision of the flange 6 is highly important as it restricts the jetting action of the water and removal of the earth to the area within the flange 6 thereby causing a hole to be formed of the exact size and shape to admit the pile. This, so far as I am aware, is novel. By removing no more material than is necessary to form a hole of the necessary size, economy is attained as well as rapidity in sinking the pile, and in addition to this, the jetting action of the entering water on account of being restricted to a surface of limited area is thus concentrated and more energetic in its action, than where it is unconfined and permitted to dissipate in all directions from the bottom of the pile. The removal by pumping the material after it has been loosened by the jetting action also greatly facilitates the sinking of the pile and so far as I am aware, is also novel. In jetting down through sand, the sand is readily loosened by the action of the water, but when hard material is encountered, such as clay or hard-pan, I introduce an abrasive in the water such as sharp sand. By forcing water mixed with sharp sand down through the pipes 11 and causing it to be discharged with force upon the material at the bottom of the pile, the material is readily loosened and removed, thereby making it possible to sink the piles through earth formations harder than sand, which so far as I am aware, has not heretofore been possible by any construction of jetting apparatus heretofore employed.

The lower ends of pipes 11 and 12 are provided with screw couplings 14 and at their upper ends are jointed by couplings 15 secured by set screws so that the pipes can be operated at the top to unscrew them at the bottom and enable their removal after the pile is sunk.

In Figs. 2 and 3, I have shown a modified form in which the pile is cylindrical in cross section instead of being rectangular, the construction following in other particulars the preceding form except that I have shown a cylindrical metal outer casing 13. In this form I have shown but a single inlet pipe 11 and a single suction pipe 12.

It should be understood that the pile may be used for bridges, wharves, dams, breakwaters, or in any other capacity.

What I claim is:—

1. A concrete pile comprising a concrete body, a depending flange projecting from the lower end of said body, and means for introducing a jetting stream along the body into the space inclosed by said flange.

2. A concrete pile comprising a concrete body, a depending flange projecting from the lower end of said body forming an inclosure,

and means for introducing a jetting stream through the body into the space inclosed by said flange, and means for removing material as it accumulates within said flange.

3. A pile comprising a concrete body with a hollow inclosure at its lower end, and means for directing a jetting stream into said inclosure whereby the action of said jetting stream is confined to the end of the area of the inclosure.

4. A pile comprising a concrete body with a hollow inclosure at its lower end, an inlet pipe for the introduction of water under pressure extending into said inclosure at one side thereof, and an outlet pipe for the removal of material extending into said inclosure at the other side thereof.

5. A pile comprising a concrete body with reinforcements extending longitudinally and laterally thereof, a metallic depending flange at its lower end forming an inclosure, an inlet pipe extending through said body and communicating with said inclosure, and an outlet pipe extending along said body and communicating with said inclosure.

6. A pile comprising a reinforced concrete body, with a footing and a hollow inclosure below the footing, a series of inlet pipes extending along the body through the footing and communicating with said inclosure, and a series of outlet pipes extending along said body and through the footing communicating with said inclosure.

7. A pile comprising a reinforced concrete body, a metallic depending flange at the lower end of the body forming an inclosure, said body having longitudinal flanges at diagonally opposite corners, an inlet pipe extending along said body and communicating with the inclosure at the lower end thereof, and an outlet pipe extending through said body and communicating with the inclosure.

8. A pile comprising a reinforced concrete body, with longitudinal flanges at diagonally opposite corners, each longitudinal flange having a vertical groove forming a key seat, an inclosure at the lower end of the pile, and means for introducing water through and removing material therefrom.

9. A pile comprising a reinforced concrete body, with a hollow inclosure at its lower end, a series of inlet pipes extending through the body and communicating with said inclosure, and a series of outlet pipes extending through said body and communicating with said inclosure, said pipes having screw couplings at the bottom enabling their removal.

In testimony whereof, I have hereunto set my hand at Los Angeles, California, this 7th day of January 1910.

E. D. McDONALD.

In presence of—

G. T. HACKLEY,

FRANK L. A. GRAHAM.
